Inventor:

JOHN T. MOORE,

D. Anthony Deiva
his Attorney.

UNITED STATES PATENT OFFICE.

JOHN T. MOORE, OF ATLANTA, GEORGIA.

RAILWAY SWITCH.

1,423,005.

Specification of Letters Patent. Patented July 18, 1922.

Application filed May 18, 1922. Serial No. 561,321.

To all whom it may concern:

Be it known that I, JOHN T. MOORE, a citizen of the United States, and resident of Atlanta, in the county of Fulton and State 5 of Georgia, have invented certain new and useful Improvements in Railway Switches, of which the following is a specification.

This invention relates to railway switches and more particularly to railway tongue 10 switches, and has for its object the prevention of the loss of energy due to arcing between the switch tongue and the switch body.

Another object of the invention is to provide a switch of the class described, provided with an electrical bond of high conductivity intimately attached to the switch tongue and the switch body.

A still further object of the invention is 20 to provide a switch of the class described having the novel combination of parts described in the following specification and claims, and illustrated in the accompanying drawings in which—

25 Figure 1 is a plan view of a portion of a switch structure embodying my invention.

Figure 2 is a sectional elevation on the line II—II of Figure 1.

30 Figure 3 is a sectional plan on the line III—III of Figure 2.

Referring more particularly to the drawings, the numeral 2 designates the switch body as a whole which has the usual tread and guard surfaces, and is provided with 35 a tongue bed 3 having a circular recess 4 adjacent its rear end. A switch tongue 5 is mounted in the bed 3 and is provided with an enlarged circular heel 6 adapted to fit snugly within the recess 4. A lug 7 projects 40 from the bottom of the heel 6 and is adapted to pass through a suitable aperture in the bottom wall of the recess 4 and into a suitable recess 8 below the tongue bed.

A suitable lever 9 is mounted in the recess 45 8 and is fulcrumed on a projection 10. The lever 9 has one end forked as at 11 to fit around the projection or lug 7 on the switch tongue 5, and has its other end provided with a boss 12 which is threaded to receive a screw 50 13 having a jam nut 14 thereon.

The recess 8 has a portion thereof opening through the upper face of the switch body at 15, and a suitable cap 16 is provided for closing this opening. The cap 16 has a 55 socket 17 in its under face adapted to fit

the head of the screw 13 and thus prevent accidental turning thereof.

In order to prevent the loss of energy between the switch body and switch tongue, I provide a flexible bond 18 of high conductivity which has one end secured to the lug 7 by welding or otherwise as at 19, and its other end is secured to the switch body 2 as at 20 by welding or otherwise. The bond 18 is preferably composed of flexible copper 60 strands laid up spirally, although any suitable material and construction may be used. However, the bond should be of sufficient length to permit attaching or securing the ends to the lug 7 and to the switch body 70 before the switch tongue 5 is mounted in position. After the bond 18 is secured to the lug 7 and switch body 2, the bond is passed through the aperture in the bottom wall of the recess 4 and forms a coil in the recess 8. 75

Experience has shown that 80 per cent of energy is saved by providing the bond 18 between the switch tongue 5 and the switch body 2.

While I have shown and described only 80 one specific embodiment of my invention, various modifications will readily suggest themselves to those skilled in the art, and may be made without departing from the scope of my invention as defined in the ap- 85 pended claims.

I claim—

1. A switch comprising a body portion, a movable tongue mounted on said body portion, and means for electrically bonding said 90 tongue to said body.

2. A switch comprising a body portion, a movable tongue mounted on said body portion, and a metallic bonding member secured to said tongue and to said body portion to 95 form an electrical bond between said tongue and said body.

3. A switch comprising a body portion, a movable tongue mounted on said body portion, and a flexible metallic bond secured to 100 said tongue and to said body portion to form an electrical bond between said tongue and said body.

4. A switch comprising a body portion, a movable tongue mounted on said body portion, and a metallic bonding member having a relatively higher conductivity than 105 said switch, said bonding member being secured to said tongue and the said body portion.

5. A switch comprising a body portion, a movable tongue mounted on said body portion, and a flexible metallic bonding member secured to said tongue and to said body portion, said bonding member having a relatively higher conductivity than said switch.

6. The combination with a switch comprising a body portion having a tongue bed therein, and a movable tongue mounted in said bed and having a downwardly projecting lug extending through a suitable aperture in the tongue bed and into a recess below said bed, of a flexible bond secured to said lug and to said switch body, substantially as described.

7. A switch comprising a body portion having a tongue bed therein, a movable tongue mounted in said bed, means for holding the tongue in said bed including a down-

wardly projecting portion and a flexible bond secured to said projecting portion and to said switch body.

8. A switch comprising a body portion having a tongue bed therein, a movable tongue mounted in said bed, and having formed thereon a downwardly projecting lug extending through a suitable aperture in the tongue bed and into a recess below said bed, a member in said recess engaging said lug to prevent upward movement of the tongue relatively to said bed, and a flexible bond of higher conductivity than the switch secured to said lug and to the switch body.

In testimony whereof I have hereunto set my hand.

JOHN T. MOORE
